[57] CLAIM

The ornamental design for seat, as shown and described.

DESCRIPTION

FIG. 1 is a front perspective view of a seat showing my new
design;

FIG. 2 is a front view thereof;

FIG. 3 is a side elevational view thereof, the opposite side
elevational view being a mirror image thereof;

FIG. 4 is a rear elevational view thereof;

FIG. 5 is a top view thereof;

FIG. 6 is a front perspective view of a second embodiment
of the seat;

FIG. 7 is a rear perspective view thereof;

FIG. 8 is a top view thereof;

FIG. 9 is an enlarged partial front perspective view of the
seat arm shown with the tassel removed for illustrative
purposes; and,

FIG. 10 is an enlarged partial view of the seat arm.

The side view of the second embodiment is as shown in FIG.
